UNITED STATES PATENT OFFICE.

HENRY S. BREWINGTON, OF BALTIMORE, MARYLAND.

SAFETY-PIN.

SPECIFICATION forming part of Letters Patent No. 606,374, dated June 28, 1898.

Application filed November 13, 1897. Serial No. 658,485. (No model.)

To all whom it may concern.

Be it known that I, HENRY S. BREWINGTON, a citizen of the United States, residing at Baltimore city, State of Maryland, have invented 5 a new and useful Safety-Pin, of which the following is a specification.

My invention relates to safety-pins, and more especially to that class of safety-pins made wholly of wire, one end of which forms the 10 pin and the other the shield to receive the point of the pin when in use.

The object of my invention is to provide a safety-pin of this class with an improved shield for the point which shall be simple, 15 cheap, strong and durable and which will permit of the ready entrance of the point of the pin into the shield from either side of approach thereto.

With this object in view my invention consists in a safety-pin and point-shield made of 20 a single piece of wire, one end of which is pointed to form the pin proper, the central portion being coiled to form the spring, the main body of the pin, which connects the 25 shield with the spring-coil, being substantially parallel to the pin portion, and the outer end of the body portion being bent upward and given a return-bend substantially in the reverse of the direction of the body 30 portion, thence bent to form a single coil upon one side of its return-bend, thence over the outside of the return-bend, and again bent on the opposite side of the return-bend to form another coil, these coils, with their connecting 35 portion and the return-bend of the body, forming the shield to receive the point of the pin when locked in position.

In order to enable others skilled in the art to which my invention most nearly appertains to make and use the same, I will now proceed to describe its construction and operation, reference being had to the accompanying drawings, forming part of this specification, in which—

Figure 1 is a perspective view of a safety-pin constructed in accordance with my invention, with the pin in its open position and shown in its closed position in dotted lines. Fig. 2 is a view of the same in side elevation, 45 the pin being locked in the shield. Fig. 3 is a top plan view of the pin as shown in Fig. 2. Fig. 4 is a fragmentary detail perspective

view of the shield and a portion of the body, part of the pin being shown in dotted lines. Fig. 5 is a top plan view of the shield and 55 the point end of the pin proper in position in the shield. Fig. 6 is a transverse vertical sectional view taken on the line 6-6 of Fig. 2, looking in the direction of the arrow. Fig. 7 is a view in elevation of the shield end of the pin. 60

Like letters of reference mark the same parts wherever they occur in the various figures of the drawings.

Referring to the drawings by letters, A is the pin proper, formed of one end of the piece 65 of wire of which the whole safety-pin is constructed by sharpening its point, as at B. At the point C the wire is bent to form a coil and a half, which end at D, from whence the main body E of the safety-pin is carried rearward 70 to a point F equidistant with the point B of the pin proper from the coil at the opposite end of the pin. From the point F the wire is curved upward and then given a return-bend, as at G, from which point it is bent to 75 form a coil H on one side, which ends at the point I, from whence the wire is bent at J over the top of the return-bend G, and again bent into the form of a coil K, which ends at the point L against the cross-bend J. 80

The coils H and K begin and end at the same point, which is directly in a vertical line with the point B of the pin A, and their inner portions are slightly apart to permit of the free entrance of the point of the pin between them 85 when passed under them from either side, and the location of the bend J with reference to the coils, as well as the location of the coils themselves, will cause the pin-point when pressed toward the shield to slide off the bend 90 J of the shield upon one side or the other. The only possibility of the pin being prevented from sliding off one side of the bend J would be for it to be pressed directly upon the center of that bend and by an unvarying 95 straight-line pressure.

The operation of my improved safety-pin is substantially the same as most safety-pins as now made, which operation consists in piercing the material with the pin portion A and 100 then pressing the point inward toward the main body until it can be adjusted into the shield from below.

From the foregoing description it will be

apparent that I have produced an exceedingly cheap, simple, strong, and durable pin of the class described, and while I have illustrated and described what I consider to be 5 the best means for carrying out my invention I do not wish to be understood as restricting myself to the exact details of construction shown and described, but hold that any slight changes, such as might suggest themselves to 10 the ordinary mechanic, would properly fall within the limit and scope of my invention.

Having thus fully described my invention, what I claim as new, and desire to secure by 15 Letters Patent of the United States, is—
15 The herein-described safety-pin, formed of

a single piece of wire, comprising the pin proper A, the body E, the connecting spring-coil, the curve beyond the pin-point beginning at the point F, turned back and continued to form the coil H, the evenly-bent 20 coil K on the opposite side of the body of the pin, and the cross-bend J on the outside of the body of the pin connecting the two coils, the end of the wire of which the pin is made abutting, at L, against the cross-bend J, all 25 substantially as described.

HENRY S. BREWINGTON.
